(57) **CLAIM**

An ornamental design for a towable water sports equipment,
as shown and described herein.

DESCRIPTION

FIG. 1 is a right side perspective view thereof as taken from
the upper right, the left side perspective view as taken from
the upper left being a mirror image thereof;

FIG. 2 is an upper front perspective view as taken from the
front upper right, the left side perspective view as taken from
the upper left being a mirror image thereof;

FIG. 3 is a top plan view thereof; and,

FIG. 4 is a bottom perspective view of a towable water
sports equipment of the present invention showing my new
design.
